UNITED STATES PATENT OFFICE

2,358,955

LIGHTER WITH FLUID RESERVOIRS

Alexander Sydney Weston, New York, N. Y.

Application November 20, 1942, Serial No. 466,305

5 Claims. (CL. 67—7.1)

This invention relates to cigarette and cigar lighters and has for its main object to provide a device of this character and of novel construction which will be more efficient than the devices now used for such purposes.

Another object of my invention is to provide a device of this type in which reserve fluid for the lighter will be embodied in a convenient manner.

Still a further object of my invention is to provide a novel efficient cigar and cigarette lighter, having a reserve fluid container or tank incorporated therein, which also will have another container or chamber for reserve flints.

Still a further object of my invention is to provide a device, as characterized hereinbefore, in which the arrangement of the flame producing device proper will be the reverse to that now used, whereby a liquid container may be arranged in the lower part thereof so that said container in the usual position of the device will be in a normal vertical position in the base thereof, the bottom of the fluid container being downwardly, and the open top thereof, with its removable cover, being upwardly.

Other objects of this invention will be apparent as the specification of the same proceeds, and among others I may mention: to provide a lighter of the type indicated which still will be simple and compact in construction, comparatively inexpensive to manufacture, adapted to be manufactured from plastic or other materials, and which will have a novel attractive appearance.

In the drawing forming a part of this specification, and accompanying the same.

Fig. 1 is an elevational view of my novel cigar and cigarette lighter in a closed position;

Fig. 2 is a bottom view thereof;

Fig. 3 is a top or plan view;

Fig. 4 is a partly sectional elevational view, the section being indicated by line 4—4 of Fig. 2;

Figs. 5 and 6 are cross sectional views, the respective sections being indicated by the lines 5—5 and 6—6 of Fig. 4;

Fig. 7 is a top, or plan, view of the lower part, or base, of my invention with the upper part, or lighter proper, having been removed from the same.

Referring now to the drawing more in detail by characters of reference, the numeral 10 indicates my complete and closed lighter in general, the same being composed of a lower hollow cylindrical, or base, portion, generally indicated by the numeral 11, and an upper lighter proper, or flame

producing device, generally indicated by the numeral 12.

As has been mentioned, the lower, base, portion is a hollow cylinder 13, which is divided by the wall 16 into the upper part 14, and a lower part 15. Both, the upper end 17 and the lower 18 of the base, are open.

The upper portion or lighter proper 12 of the device may also have a casing or outer housing 19 of any appropriate construction, well known in this art, from which projects cylindrical downward extension 20 of a reduced diameter, compared to the upper main portion 21 of the housing 19.

The lighter proper or flame producing device 22, arranged in the upper housing or casing 19, preferably is of the type which operates by a friction wheel 23, rubbing on a flint (not shown) producing sparks, and igniting the wick 24 fed by a combustible liquid from the housing 22, as it is well known.

Housing 22 of the flame producing device is secured in the casing 19 by friction so that anytime it is desired it may be pulled out from the same. It may have an open inner end, or it may have an opening at its inner end, to refill the same, that is, to again saturate the usual cotton mass, in the housing 22, with the combustible liquid.

The construction of and parts in the lighter proper, or flame producing device, 22 are not shown as they are well known in this art.

It will be seen that the lighter proper, or flame producing device, 22, normally is arranged in my device in an inverted position and the wheel 23 and wick 24 are pointing downwardly, being housed in the space 14a in the upper part 14 of the hollow base 11 of my device.

In the space 15a in the lower portion 15 of the base 13 is arranged a reserve fluid container or tank 25 having an open top 26 normally sealed by a screw threaded cap 27.

Outer screw threads 28 are provided on the lower part of the reserve fluid tank 25, and corresponding inner threads are provided on the wall of the base 13, adjacent to its open end 18, whereby said reserve container or tank may be removably secured in the lower part of the base, as will be obvious.

It will be seen that in a normal position of my device the reserve container 25 will be in its normal position, its closed bottom 29 being downwardly and its opening 26 upwardly.

The upper end 30 of the casing or housing 19 for the lighter proper 22, is closed and preferably

shaped as indicated in Figs. 1 and 4, and has an upwardly extending hollow sleeve projection 31 open at the top and provided with screw threads 32 cooperating with the screw threads in a corresponding recess in the closure ball 34.

The space 31a in the sleeve 31 may serve as a chamber or magazine for the reserve flints 35, and an additional cork, rubber or similar stopper 36 may be used to close the upper end of the sleeve 31, mainly to prevent the rattling of the flints 35.

From a shoulder 37 at the lower end of the casing 19, where the cylindrical projection 20 starts, semi-cylindrical guide and securing projection 38 extend downwardly, on the outer wall of the cylindrical projection 20, and corresponding recesses 39 are provided in the inner wall of the upper end of the upper portion 14 of the base casing or housing 13, and when my device is in a closed position, as indicated in Figs. 1 and 4, said guide and securing projections 38 will be pushed into the recesses 39. In this manner the projection 20 and the upper casing 19 may be pushed into the upper end of the base 13, said projections 38, in the recesses 39, guiding such a movement, and afterwards preventing, through their increased frictional action, an easy removal or dropping out of the upper casing 19 from the lower or base housing 13. Some noticeable force will be necessary to push the extension 20 of the upper casing 19 into the upper portion of the base 13, and, similarly, some exertion will be necessary to pull the extension 20 out of the base.

The guide projections 38, and the corresponding recesses 39, also will prevent a rotation of the upper portion 19 in the base 13.

Columns, or longitudinal projections, 40 may be provided on the outside of the base 11 and the upper portion 10 to reinforce the upper and lower casings or housings, and thereby to make it possible to manufacture them out of plastic material, with desirable thin walls, said columns 40 also serving as grips on the two parts so that they may be pulled apart without causing them to rotate or turn with reference to one another, and said columns obviously serve to give the device a more attractive and esthetic appearance.

The use and operation of my cigar and cigarette lighter will be obvious from the herein description.

Normally, my lighter is in the position as indicated in Fig. 4. When it is desired to use the same, the upper casing 19 will be gripped with one hand and the base 13 with the other, and the upper casing 19 with its associated devices will be pulled out of the base, and turned upwardly into a reverse position to that shown, and then operated as usual.

After having used the lighter, the upper portion 10 of the same will again be turned into an inverted position, with the extension 20 thereof downwardly, when the exposed part of the lighter proper 22 may be pushed into the upper end of the base.

When the combustible liquid in the lighter proper 22 has been used up, and wick 24 does not produce the ready flame any more, said lighter proper 22 will be pulled out of the upper casing or housing 19 and refilled with combustible liquid from the reserve tank 25.

For this purpose an operating slot or recess 41 is provided in the bottom 29 of said tank and by inserting any appropriate object, even a coin, into said slot, the tank 25 may be removed from the space 15a in the base, by unscrewing, where-

upon its cap may be removed to use a part of the fluid therein.

It will be obvious that in a reverse manner, the reserve fluid container 25 again may be secured in the lower space of the base by said screw threaded engagement.

Similarly, when the flint in the lighter proper, or flame producing device, 22 has been used up, the same may be replaced by one of the reserve flints 35, in the sleeve chamber or magazine 31, at the upper end of the device, for which purpose the ball shaped closure cap 34 will be unscrewed, stopper 36 removed, and after taking out a reserve flint 35, the stopper 36 and the closure ball 34 may be replaced into their original positions.

It will be obvious that said closure ball may also be used as a grip for pulling the housing 19 out of the base 11, and said ball, with an appropriate shaping of the closed upper end 30 of said housing, will aid in the attractive, esthetic appearance of my device.

As has been mentioned hereinbefore, my device may conveniently be made of plastic material by simple die operations, with the exception of the housing 22 for the lighter proper, which 25 I prefer to make of sheet metal, as is the case with lighters used at present.

It also will be observed that the ornamental and reinforcing columns 40 may preferably be placed in the diameters where the recesses 39 are provided in the upper end of the base, so that the wall of said base may be kept comparatively thin and still have large enough recesses 39 for the guide projections 38 in the casing 19.

What I claim as new, is:

1. In a cigar and cigarette lighter, in combination, a tubular base casing open at both ends, a transverse partition wall in said casing intermediate its ends forming an upper and a lower space in said casing, a lighter device proper removably inserted in said upper space, and a fuel container removably secured in said lower space, a casing for said lighter proper, the lower end thereof slidably fitting into the upper opening of 45 said base casing, longitudinal projections on said lighter casing, and corresponding depressions in the wall of said base casing, thereby to guide said lighter casing when entering or leaving said base casing and to prevent a rotary movement thereof 50 during said operations.

2. In a cigar and cigarette lighter, in combination, a tubular base casing open at both ends, a transverse partition wall in said casing intermediate its ends forming an upper and a lower space in said casing, a lighter device proper removably inserted in said upper space, and a fuel container removably secured in said lower space, a casing for said lighter proper, the lower end thereof slidably fitting into the upper opening of 60 said base casing, longitudinal projections on said lighter casing, and corresponding depressions in the wall of said base casing, thereby to guide said lighter casing when entering or leaving said base casing and to prevent a rotary movement thereof 65 during said operations, and longitudinal columnar projections on said base casing, in the diameters of said depressions, for reinforcing said base casing, generally, and particularly at the places of depression, and thereby permitting it 70 to be made with lighter walls, and also to provide grips when using the device.

3. In a cigar and cigarette lighter, in combination, a tubular base casing open at both ends, a transverse partition wall in said casing intermediate its ends forming an upper and a lower space

in said casing, a lighter device proper removably inserted in said upper space, and a fuel container removably secured in said lower space, a casing for said lighter proper, the lower end thereof slidably fitting into the upper opening of said base casing, the outer surface of said casing for the lighter generally being in continuation of the outer surface of said tubular base casing, said lighter casing widening towards its end to provide a better grip when removing the same.

4. In a cigar and cigarette lighter, in combination, a tubular base casing open at both ends, a transverse partition wall in said casing intermediate its ends forming an upper and a lower space in said casing, a lighter device proper removably inserted in said upper space, a casing for said lighter proper, the lower end thereof slidably fitting into the upper opening of said base

casing, the outer surface of said casing for the lighter generally being in continuation of the outer surface of said tubular base casing, a container projecting into said lower space, its bottom closing the same, and forming the bottom of the lighter.

5. In a cigar and cigarette lighter, in combination, a tubular base casing open at both ends, a transverse partition wall in said casing intermediate its ends forming an upper and a lower space in said casing, a lighter device proper removably inserted in said upper space, a casing for said lighter proper, the lower end thereof slidably fitting into the upper opening of said base casing, a container projecting into said lower space, its bottom closing the same, and forming the bottom of the lighter.

ALEXANDER SYDNEY WESTON.
